UNITED STATES PATENT OFFICE.

**JAMES WILLIAM BALL, OF LOGANSPORT, INDIANA, ASSIGNOR TO FRANK R. GREENE,
OF CHICAGO, ILLINOIS.**

DESIGN FOR A COMPUTING-SCALE CASING.

52,109.

Specification for Design.

Patented June 18, 1918.

Application filed March 21, 1918. Serial No. 223,841. Term of patent 14 years.

To all whom it may concern:

Be it known that I, JAMES WILLIAM BALL, a citizen of the United States, residing at Logansport, in the county of Cass and State of Indiana, have invented a new, original, and ornamental Design for a Computing-Scale Casing, of which the following is a specification, reference being had to the accompanying drawing, forming part thereof.

Figure 1 is a front elevation of my scale casing;

Fig. 2 is an end elevation.

I claim:—

The ornamental design for a computing scale casing as shown.

JAMES WILLIAM BALL.
